Des. 214,661

Patented July 15, 1969

214,661

PORTABLE ELECTRICAL APPLIANCE HANDLE

Martin J. Wolff, New Haven, Conn., assignor to Sperry Rand Corporation, New York, N.Y., a corporation of Delaware

Filed June 17, 1968, Ser. No. 12,394

Term of patent 14 years

Int. Cl. D4—02

U.S. Cl. D4—14

Fig. 1.

Fig. 2.

Fig. 3.

Fig. 4.

Fig. 5.

FIG. 1 is a rear perspective view of a portable electrical appliance handle showing my new design;

FIG. 2 is a side view thereof;

FIG. 3 is a bottom view thereof;

FIG. 4 is a front view thereof; and

FIG. 5 is a rear view thereof.

The broken lines shown in FIG. 1 of the drawing are for illustrative purposes only.

I claim:

The ornamental design for a portable electrical appliance handle, substantially as shown and described.
